UNITED STATES PATENT OFFICE.

BERNHARD DREYFUS, OF NEW YORK, N. Y.

DESIGN FOR A PENDANT.

SPECIFICATION forming part of Design No. 15,750, dated January 27, 1885.

Application filed September 17, 1884. Term of patent 7 years.

To all whom it may concern:

Be it known that I, BERNHARD DREYFUS, of the city, county, and State of New York, have invented and produced a new and original Design for Pendants, of which the following is a full, clear, and exact description.

This invention relates to a new and ornamental design for pendants.

Reference is to be had to the accompanying drawing, forming part of this specification, in which a face view of my newly-designed pendant is shown.

A B are two egg-shaped or oval chenille balls or tufts. C is a disk between said balls or tufts, having beveled or inclined upper and lower surfaces. D are radial cords or strands on the disk. The cords D extend from the center of one side over the rim to the center of the other side. E is a ball or bead on the upper end of the upper ball or tuft, A, and E' is a ball or bead on the lower end of the lower ball or tuft, B. F is a loop on the upper ball or bead, E.

I claim—

1. The herein-described design for a pendant, consisting of the egg-shaped balls or tufts A B, and an interposed disk having beveled or inclined upper and lower surfaces, as shown. 25
2. The herein-described design for a pendant, consisting of the egg-shaped balls or tufts A B, and the interposed beveled or inclined disk C, having the radial cords D extending over its upper and lower surfaces and its rim, as shown. 30
3. The herein-described design for a pendant, consisting of the egg-shaped balls or tufts A B, the interposed beveled or inclined disk C, having radial cords D, the balls or beads E E' on the upper and lower ends of the balls or tufts A B, respectively, and the loop F on the 40 bead or ball E, as shown.

BERNHARD DREYFUS.
